MANUFACTURE OF PROPELLER BLADES

Charles A. Brauchler, Canton, Ohio

Application July 7, 1941, Serial No. 401,303

7 Claims. (Cl. 29—156.8)

The invention relates to the manufacture of propeller blades for airplanes, and more particularly to a novel method of making hollow, metal blades formed by forging operations.

The general object of the invention contemplates an improved construction of hollow metal propeller blade with integral, internal reinforcing means, and a novel method of forming the blade by forging operations.

A further object of the invention is to provide a method of making a hollow metal propeller blade which is internally reinforced by integral, longitudinal reinforcing ribs.

Another object is to provide a method of making a hollow metal propeller blade formed from a single plate of metal having a tapered, longitudinal corrugation formed through its median line to form the leading edge of the propeller blade.

Still another object is to provide for the manufacture of the blade from such a plate in which longitudinal ribs are formed on opposite sides of the central corrugation and adapted to be welded together at their butting edges when the plate is bent along said median corrugation.

A further object is to provide for making a hollow propeller blade in which the opposite side edges of the plate blank are welded or otherwise connected together.

A still further object of the invention is to provide a novel method of forming a propeller blade which consists in forging a flat blank from a metal plate, the blank being tapered in thickness from the hub and toward the tip and provided with a central longitudinal tapered corrugation in one surface and longitudinal ribs upon its other surface, the blank being then heated and curved longitudinally from end to end to conform to the desired contour of the leading edge of the finished blade after which the blank is folded or bent upon itself along its medial line and the opposite edges of the blank are welded together and the meeting edges of the ribs are welded together forming a hollow reinforced metal blade of the desired contour.

The above objects, together with others, which will be apparent from the drawings and following description, or which may be later referred to, may be attained by constructing the improved hollow metal propeller blade in the manner hereinafter described in detail, and illustrated in the accompanying drawings, in which

Figure 1 is a plan view of the forged blank from which the improved propeller blade is formed;

Fig. 2, a longitudinal edge elevation of the blank shown in Fig. 1;

Fig. 3, an elevation of the hub end of the blank;

Fig. 4, a transverse cross-sectional view through the blank, taken as on the line 4—4, Fig. 1;

Fig. 5, a transverse cross-sectional view through the blank, taken as on the line 5—5, Fig. 1;

Fig. 6, a transverse cross-sectional view of the blank, taken as on the line 6—6, Fig. 1;

Fig. 7, a transverse cross-sectional view of the blank, taken as on the line 7—7, Fig. 1;

Fig. 8, a transverse cross-sectional view of the blank, taken as on the line 8—8, Fig. 1;

Fig. 9, a transverse cross-sectional view of the blank, taken as on the line 9—9, Fig. 1;

Fig. 10, a transverse cross-sectional view of the blank, taken as on the line 10—10, Fig. 1;

Fig. 11, a longitudinal edge elevation of the blank after the same has been longitudinally bent or cambered to conform to the desired contour of the leading edge of the finished blade;

Fig. 12, a plan view of a completed propeller blade formed in accordance with the invention;

Fig. 13, an edge view of the completed propeller blade;

Fig. 14, a transverse sectional view through the completed propeller, taken as on the line 14—14, Fig. 11;

Fig. 15, a transverse sectional view through the blade, taken as on the line 15—15, Fig. 11;

Fig. 16, a transverse sectional view through the blade, taken as on the line 16—16, Fig. 11;

Fig. 17, a transverse sectional view through the blade, taken as on the line 17—17, Fig. 11;

Fig. 18, a transverse sectional view through the blade, taken as on the line 18—18, Fig. 11;

Fig. 19, a transverse sectional view through the blade, taken as on the line 19—19, Fig. 11;

Fig. 20, a transverse sectional view through the blade, taken as on the line 20—20, Fig. 11; and

Fig. 21, a transverse sectional view through the blade, taken as on the line 21—21, Fig. 11.

Similar numerals refer to similar parts throughout the drawings.

The improved propeller blade to which the invention pertains may be formed of steel or other suitable metal of conventional exterior form being of hollow construction provided with longitudinal internal reinforcing ribs.

The blade may be formed from a rectangular steel plate or heavy sheet of the general shape indicated by the dot and dash outline 25 in Fig. 1.

This plate or sheet is heated to forging temperature and roll forged in a machine of the

general type of the Ajax roll forging machine in which substantially semi-circular die portions are provided upon two cooperating rolls between which the heated metal plate is passed.

The rolls of this forging machine having cooperating die impressions for producing the blank as shown in Figs. 1 to 10, inclusive. This blank is preferably tapered from the hub and toward the tip end and provided through its longitudinal center with tapered corrugation 26 which is enlarged and substantially semi-cylindric in form at the hub end of the blank as indicated at 27, the metal being preferably thickened throughout the tapered portion of the corrugation 26 as indicated at 28.

Straight parallel longitudinal ribs 29 and 30 are formed on the opposite side of the blank and on each side of the center thereof and extending from a point near the hub and to a point spaced from the tip end of the blank, these ribs being tapered toward the tip end of the blank as best shown in Fig. 2.

The blank is then sheared to the outline shown in full lines in Fig. 1 forming the similar opposite side edges 31.

The blank thus formed is then heated and placed in suitable forging dies where it is pressed or hammered to the form shown in Fig. 11, the entire blank being given a longitudinal cambered curve indicated generally at 32, conforming to the desired contour of the leading edge of the completed blade.

The next step in the method of forming the blade consists in bending or folding the cambered blank shown in Fig. 11 upon itself along its medial longitudinal line, that is, through the axis of the corrugation 26.

This bending or forming may be performed by first reheating the blank, or if desired, the blank may be bent cold. This bending or forming operation is accomplished by pressing or hammering the preferably heated, cambered blank of Fig. 11, folding it upon itself along the central corrugation 26 and substantially flattening the blank on opposite sides of said corrugation, thus bringing opposite edges of the blank into contact with each other.

The edges 31 of the blank are brought into contact with each other and welded together as indicated at 31a in Figs. 14 to 21, inclusive, and the edges of the ribs 29-29 and 30-30 are brought into contact with each other and welded together as indicated at 33 and 34, respectively.

The reinforced tapered corrugation 26 thus forms the leading edge of the blade 35 shown in Figs. 12 to 21, inclusive, while the welded edges 31 of the blank form the opposite edge of the blade.

The flat portions 36 at the hub end of the blank, at each side of the cylindric enlargement 27 are curved and form a complete hollow cylindric hub portion 37.

If it is desired to form a collar as at 38 upon the hub end of the blade the blank may be made sufficiently longer to permit this collar to be offset thereon.

By this method a hollow internally reinforced metal blade is formed having an integral reinforced leading edge portion and two continuous walls permanently united at their meeting edges 70 to form the other edge of the blade.

I claim:

1. The method of making a hollow metal propeller blade which consists in forming a generally flat blank with a medial, longitudinal con-

cavo-convex corrugation on one side thereof, said corrugation being tapered from one end of the blank toward the other end thereof, then curving the entire blank longitudinally to shape said corrugation to the desired contour of the leading edge of the blade, then bending the blank upon itself along said corrugation and forming the blank so as to substantially flatten the same on opposite sides of said corrugation and bringing the opposite edges of the blank into contact with each other, and uniting said edges.

2. The method of making a hollow metal propeller blade which consists in forming a generally flat blank with a medial, longitudinal concavo-convex corrugation on one side thereof, said corrugation being tapered from one end of the blank toward the other end thereof, and with integral ribs upon each side of the corrugation, which ribs are parallel with the axis of the corrugation and equally spaced laterally therefrom and positioned on the opposite side of the blank from said corrugation, then curving the entire blank longitudinally to shape said corrugation to the desired contour of the leading edge of the blade, then bending the blank upon itself along said corrugation, and forming the blank so as to substantially flatten the same on opposite sides of said corrugation bringing the opposed edges of said ribs into contact with each other and bringing the opposite edges of the blank into contact with each other, and uniting said edges of the ribs, and uniting said edges of the blank.

3. The method of making a hollow metal propeller blade which consists in forming a generally flat blank with a medial, longitudinal concavo-convex corrugation on one side thereof, said corrugation being tapered from one end of the blank toward the other end thereof, and with integral ribs upon each side of the corrugation, which ribs are parallel with the axis of the corrugation and equally spaced laterally therefrom and tapered in the same direction as said corrugation and positioned on the opposite side of the blank from said corrugation, then curving the entire blank longitudinally to shape said corrugation to the desired contour of the leading edge of the blade, then bending the blank upon itself along said corrugation, and forming the blank so as to substantially flatten the same on opposite sides of said corrugation bringing the opposed edges of said ribs into contact with each other and bringing the opposite edges of the blank into contact with each other, and uniting said edges of the ribs, and uniting said edges of the blank.

4. The method of making a hollow metal propeller blade which consists in forming a generally flat blank tapered in thickness from one end toward the other end with a medial, longitudinal concavo-convex corrugation correspondingly tapered, then curving the entire blank longitudinally to shape said corrugation to the desired contour of the leading edge of the blade, then bending the blank upon itself along said corrugation and forming the blank so as to substantially flatten the same on opposite sides of said corrugation bringing the opposite edges of the blank into contact with each other, and uniting said edges.

5. The method of making a hollow metal propeller blade which consists in forming a generally flat blank tapered in thickness from one end toward the other end with a medial, longitudinal concavo-convex corrugation correspondingly tapered, and with integral ribs upon each side of the corrugation, which ribs are parallel with

the axis of the corrugation and equally spaced laterally therefrom and positioned on the opposite side of the blank from said corrugation, then curving the entire blank longitudinally to shape said corrugation to the desired contour of the leading edge of the blade, then bending the blank upon itself along said corrugation, and forming the blank so as to substantially flatten the same on opposite sides of said corrugation bringing the opposed edges of said ribs into contact with each other and bringing the opposite edges of the blank into contact with each other, and uniting said edges of the ribs, and uniting said edges of the blank.

6. The method of making a hollow metal propeller blade which consists in forming a generally flat blank with a medial, longitudinal, concavo-convex corrugation on one side thereof, said corrugation being tapered from one end of the blank toward the other end thereof, then curving the entire blank longitudinally to shape said corrugation to the desired contour of the leading edge of the blade, then reheating the blank and forming it by bending the blank upon itself

along said corrugation so as to substantially flatten the blank on each side of the corrugation and bringing opposite edges of the blank into contact with each other and uniting said edges.

5 7. The method of making a hollow metal propeller blade which consists in forming a generally flat blank with a medial, longitudinal, concavo-convex corrugation on one side thereof, said corrugation being tapered from one end of the blank toward the other end thereof, and with integral ribs upon each side of the corrugation and on the opposite side of the blank from said corrugation, then curving the entire blank longitudinally to shape said corrugation to the desired 10 contour of the leading edge of the blade, then reheating the blank and forming it by bending the blank upon itself along said corrugation so as to substantially flatten the blank on each side of the corrugation and bringing the edges of the 15 ribs into contact with each other and uniting said ribs and bringing opposite edges of the blank into contact with each other and uniting said edges.
